(57) **CLAIM**

We claim the ornamental design for a shape punch, as shown and described.

DESCRIPTION

FIG. 1 is a first isometric view of the claimed design; FIG. 2 is a rear elevational view of the claimed design; FIG. 3 is a front elevational view of the claimed design; FIG. 4 is a right side elevational view of the claimed design; FIG. 5 is a left side elevational view of the claimed design; FIG. 6 is a top plan view of the claimed design; FIG. 7 is a bottom plan view of the claimed design; and, FIG. 8 is a second isometric view of the claimed design. The broken lines in the drawings are included for the purpose of illustrating subject matter that forms no part of the claimed design.
